UNITED STATES PATENT OFFICE

2,000,930

AIR MOTOR

Bela De Nagy, New York, N. Y.

Application February 17, 1934, Serial No. 711,637

5 Claims. (Cl. 253—134)

This invention relates to air motors and the subject matter thereof is a continuation in part of my copending application for Air motor and rotary brush, Serial No. 670,733, filed May 12th, 5 1933, the line of division between my two applications being that said copending application relates to specific embodiments of motor driven 10 polishing tools and the like, while the present application relates to a specific form of air motor and a housing therefor, adapted to drive and receive, respectively, a rotary device.

The main object of my invention is to provide an air motor which may operate with weak, low-pressure air current in a novel manner.

15 Another object of my invention is to provide a device, as characterized hereinbefore, which will be simple in construction, efficient and reliable in operation and inexpensive to manufacture, and which also may have a novel suction effect.

20 Still a further object of this invention is to provide an air motor, comprising a rotor which will permit the passage of air or other operating gas medium therethrough even when, by some unforeseen circumstance or force, said rotor is 25 prevented from operating, thereby my device remedying a serious drawback of air motors and compressors used at present in which, when the load or force operating against their rotating part becomes unduly large, the air current is prevented from egress and a harmful pressure is 30 built up back of the rotor.

In the drawing accompanying the specification and forming a part thereof:

Fig. 1 is a partly sectional plan of my device 35 in a specific embodiment providing means for attaching to my air motor a rotary brush, a cover of the device having been removed, and

Fig. 2 is a sectional elevation thereof, on an enlarged scale, the section being taken on the 40 line 2—2 of Fig. 1.

Referring now to the drawing more closely, by characters of reference, my invention is provided with a housing 10 having, in the embodiment shown, an upper compartment 11 and a lower compartment 12 and a partition wall 13 between said two compartments, said housing being generally of a cylindrical shape and placed with its axis in a vertical position. In the upper compartment 11 of the housing I arrange, a rotor or turbine 14, having a plurality of vanes 15, secured on a rotating disc 14a and terminated by outer and inner imaginary cylinder surfaces 16 and 17, respectively, as is well known in the art. The contour of the vanes 15 may be designed according to the principles of engineering science to be

most efficient for the conditions present in the particular case, but for the sake of simplicity and saving, I prefer to make them circular segments. A hub 18 is also provided for the rotor 14 by which the same is secured on a vertical shaft 19 which for this purpose may have a square portion 20 engaging said hub 18. A removable cover 21 may be provided for the housing 10 and in the center thereof may be arranged a ball-bearing, generally indicated by the numeral 22 for the 10 upper end of the shaft 19. 5

A second ball-bearing 23 may be provided on the partition 13, shaft 19 projecting through said second ball-bearing 23 and the lower end 24 of said shaft may carry an operating device proper 15 25 secured thereon and to be driven by my air motor. Said operating device proper is shown herein in the form of a circular brush 26, of any suitable construction which will constantly be pressed in a downward direction against a surface 27 to be operated on, like the floor of a room, by the helical spring 28.

The upper compartment 11 of the housing 10 is continued in an air conduit 32 through which compressed air or other gas may be introduced, 25 as indicated by the arrow 33, from any suitable source, with a pressure and velocity as desired. For a convenient and easy use of my invention said conduit 32 may be provided with means whereby it may be attached to an outlet opening on the usual vacuum cleaner and my device 30 operated therethrough.

The air will follow the internal contour of the air conduit 32 (Fig. 1) and will strike the vanes 15, as at 34, will then pass through them in a 35 certain case, that is, at a certain speed, pressure and other factors of operation, following the direction generally indicated by the dot and dash line 35 and leaving the inner openings of the vanes at 35a, will pass through the space in the 40 rotor following the line 36 and will exit following the center line 37 striking the vanes once more at the opposite side of the rotor so that the same air current will act on the vanes a second time. For the exit of the air, openings 39 are provided 45 in the wall of the compartment 11 substantially opposite to the conduit 32 and being spread at that portion of said wall to a certain distance. In the case indicated in Fig. 1 the air current substantially will have the limits indicated by the lines 40 and 41 and the outer limits of its exit are indicated by the lines 42 and 43. Under other circumstances, the direction, width, and spread of 50 exit of said air current might be different but it 55

will generally follow the conditions shown in passages; a rotor in horizontal alignment with said passages; means for rotating an operating device in the lower compartment when the rotor is driven by air currents passing through the upper compartment; and means in the said separating wall permitting air to be drawn from the lower chamber through the outlet passage when the rotor is in operation said rotor having curved vanes leaving a free space around the center thereof to permit an air stream to pass from the inlet through a portion of the vanes then through the central space and then through the vanes at a second portion of the rotor.

The air will have the shortest exit and most efficient route through my device. It will act twice on the vanes, as has been explained hereinbefore, and the air will freely pass through my device even if the rotor 14 is forced to remain idle which is a great improvement over other air turbines or motors now used. In a similar device as the one here described, with air motors of present design, if the brush 26 received an excessive pressure, or the rotor 14 would be stopped from rotation by any other cause, the current would not find any way to pass through the device and would cause undue stresses and great rise in temperature in the compressor or other source of the air, which cannot happen with my device since the air will always escape from the same.

Openings 50 may also be provided in the partition 13, being of suitable sizes and distribution and when the air or other working gaseous fluid medium will escape through the openings 39, passing through the upper compartment 11, it will have a suction effect through these openings 50 and will draw the air from the lower compartment 12 through the same, causing it to finally leave through the openings 39 with the working air stream, and the air in the compartment 12 may thereby be removed, as indicated by the arrows 51. This effect may be used for various beneficial purposes and it will be highly desirable in case a polishing, brushing or similar device is operating in said compartment 12, as indicated in the embodiment shown in the present drawing, since this suction effect will aid in removing the dust and other particles loosened by the operation of said device and it also will aid in cooling the device and the surfaces operated on. To aid in this result, further openings 52 may be provided in the back 26a of the brush 26 so that the air may find a ready passage through the brush itself, as indicated by the arrow 53.

It will be understood that changes and variations may be made in the parts and combinations of my device and I hereby reserve all my rights to any and all such changes as are within the spirit of the invention and the scope of the appended claims.

What I claim as new is:

1. In combination, a housing having annular side walls; a partition wall integral with the side walls and dividing the housing into a closed upper and a downwardly open lower compartment; a shaft revoluble in the axis of said housing; a rotor located in the upper compartment and locked to said shaft; the walls of said upper compartment being provided with intake and outlet air passages; means in the partition wall for permitting exhaustion of air from the lower chamber and means for driving an operating device received in said lower chamber when the rotor is operated said rotor having curved vanes leaving a free space around the center thereof to permit an air stream to pass from the inlet through a portion of the vanes then through the central space and then through the vanes at a second portion of the rotor.

2. An air motor comprising a housing separated by a wall into upper or motor and lower or operating device receiving compartments, the side walls of the upper compartment being provided with horizontally aligned inlet and outlet air

passages; a rotor in horizontal alignment with said passages; means for rotating an operating device in the lower compartment when the rotor is driven by air currents passing through the upper compartment; and means in the said separating wall permitting air to be drawn from the lower chamber through the outlet passage when the rotor is in operation said rotor having curved vanes leaving a free space around the center thereof to permit an air stream to pass from the inlet through a portion of the vanes then through the central space and then through the vanes at a second portion of the rotor.

3. In combination, a housing; a wall dividing said housing into upper or motor and lower or operating device receiving compartments; an air inlet conduit comprising an integral portion of said housing and being in communication with the upper compartment; bars formed from the wall of the upper compartment for providing outlet air passages arranged opposite said conduit; a rotor located in the upper compartment a shaft connecting the rotor with an operating device in the lower compartment; and means in the said dividing wall permitting air flow from the lower to the upper compartment through suction generated by the operation of said rotor said rotor having curved vanes leaving a free space around the center thereof to permit an air stream to pass from the inlet through a portion of the vanes then through the central space and then through the vanes at a second portion of the rotor.

4. In an air motor, a substantially horizontal rotor; a housing enclosing said rotor; vanes on the periphery of said rotor, said vanes stopping short of the center so as to provide a space around the axis of the rotor between the inner terminations of said vanes; means to guide a stream of air or other similar gaseous fluid medium through a part of the housing to a portion of the outer circumference of said vanes, said stream being adapted to pass through the vanes at that portion of the circumference, then through said central space, and then through the vanes at a second portion of the rotor, and means to permit the exit of said stream at a second part of the outer wall of the housing; a substantially enclosed space underneath said housing for receiving an operating device, openings being provided between the inner space of said housing and said space underneath thereof, so as to cause the air stream passing through said housing to have a suction effect on the air in said enclosed lower space.

5. In an air motor, a closed housing; a substantially horizontal rotor therein having curved substantially radial vanes with a free central space thereon; air inlet and outlet openings being provided for said housing and being substantially opposite to one another, said openings and said rotor being adapted to permit the passage of a horizontal air stream therethrough to operate said rotor, said air stream passing from the inlet through a portion of the vanes, then through the central space and then through the vanes at a second portion of the rotor; means providing a receiving space underneath said housing for an operating device; openings being provided between said housing and said receiving space to permit the passage of air in said receiving space through said housing under the suction effect of said stream of air, and thereby aid the efficient and clean operation of said device.

BELA DE NAGY.
